UNITED STATES PATENT OFFICE.

ROBERT MORRELL, OF SUMMIT, NEW JERSEY.

RAILROAD-TIE.

SPECIFICATION forming part of Letters Patent No. 365,932, dated July 5, 1887.

Application filed September 17, 1886. Serial No. 213,766. (No model.)

To all whom it may concern:

Be it known that I, ROBERT MORRELL, of Summit, Union county, New Jersey, have invented a new and useful Improvement in Railroad-Ties, of which the following is a specification.

My invention consists of improvements in the contrivance of composite metallic and wood ties, whereby these or their equivalent substances may be combined, for the advantages of the elastic wood seats for the rails and the strength of a metallic retainer therefor, in such manner as to enable the metallic portion to be constructed of thin rolled metal in such form as to afford the maximum of strength and the minimum of metal, and so as to be constructed in the simplest and most economical manner, and also so that the elastic wood seats for the rails may be most readily shifted and changed in position without removing the whole tie, particularly in tunnels and on bridges, where the walls and trusses greatly interfere with the changing of ties of full length, all as hereinafter fully described, reference being made to the accompanying drawings, in which—

Figure 1 is a diagram representing the form of the blank from which I make the metallic portion of the tie. Fig. 2 is a side elevation 30 of my improved tie. Fig. 3 is a plan view. Fig. 4 is a transverse section on line $\alpha\alpha$, Fig. 3. Fig. 5 is a transverse section on line yy , Fig. 3. Figs. 6 and 7 are side and plan views, respectively, showing a modification of the metallic retainer. Fig. 8 is a plan showing re-enforcing retaining devices for the elastic seats and rails. Fig. 9 is a section on aa , Fig. 8, and Fig. 10 is a section on bb of same figure.

The metallic portion of my improved composite tie consists of a thin sheet, a , of rolled metal, first produced in the blank form represented in Fig. 1, about the length of an ordinary tie, and about as wide as the bottom and two sides of the same, with four narrow extension flaps 45 or webs, b , projecting from each edge. The blank is then bent up at right angles along the dotted lines c , and the extension webs or flaps b are bent down flatwise along the line d over the rest, forming the complete metallic portion comprising the bottom, two sides, and top

flanges, making a substantial base support and retainer, with which I combine two elastic bearers, e , for the rails, consisting of wood or equivalent elastic blocks fitted to slide into the spaces under the top flanges, either from 55 the outer ends or from the middle space between the flanges, as most convenient, or as may be required by the position of the tie. For instance, in tunnels or on bridges the tunnel-walls and the bridge-trusses interfere with 60 the inserting and removal of the blocks at the ends. In such cases the contrivance for inserting the blocks from the middle space is an important advantage. The flanged webs b are grouped near each end of the metallic body, 65 so as to constitute two outside and two inside flanges to each rail f , which rails are seated on the bearer e , in the space between said outside and inside flanges, and the rail-spikes g are driven through notches or holes k of said 70 flanges into the wood, and the beams are also spiked through said flanges at i , if desired, for further security of the bearers, and of the flanges and the sides of the metallic body as well, which are thus prevented from spreading 75 apart, as they might in case the ties are not well bedded in the earth. The flanges furnish a substantial backing to the rail-holding spikes and effectually prevent them from being forced laterally away from the edges of the 80 rail-flanges, to which they are subject in the ordinary ties, the wood being crushed behind the spikes by the lateral thrusts of the rails against the spikes. The metallic portion of the tie is much more lasting than the ordinary 85 wood tie, and, owing to the thin light material which by my improved construction I am able to use, is, together with the bearing-pieces, not more expensive to begin with. The bearing-pieces are more lasting in the metallic portion than the ordinary wood ties, are laid directly in the earth, and said bearing-pieces 90 may be made more lasting by chemical treatment, less expensively than treating whole ties, and they may be cheaply renewed from time 95 to time. The bottom of the metallic portion may have holes j for the escape of rain from the interior. I propose in some cases to reinforce these ties with bands k' , for more firmly holding up the sides to the wood bearers, the 100

bands being driven on from the ends of the ties, or by caps *l*, fitted down over the top, one or both sides of the rails, as in Fig. 8, the caps being secured by spiking through the sides 5 into the wood, in which case the flanges *b* may be used or not, as preferred. I may also in some cases produce the outwardly-projecting top flange, *m*, along the middle portions of the sides between the flanges *b* by retaining those 10 portions of the blank, instead of cutting them away, as represented in Figs. 1, 2, and 3, and bending said portions outward for greater lateral and vertical rigidity in such cases as may require it. These metallic retaining-shells may 15 be produced in and by any of the well-known methods of the manufacture of such articles—as, for instance, long sheets may be rolled in about the width of the extreme breadth at the flanges *b*. The sheets may be fed intermittently to cutting-dies adapted to cut out the form of the blanks, and the cutting-machine may transfer the blanks to benders adapted to automatically effect the bending of the sides and flanges, as required. I will use iron, steel, 20 or any approved rolled metal that is capable of being bent, as required, in the production of the metallic part of the tie, and will probably employ wood for the elastic rail-bearing seats; but various substances may be substituted for 25 the wood—as compressed or vulcanized fiber, paper-stock, and the like, some of which productions may be made much more lasting than plain wood.

Efforts have been made to provide composite ties with cast-iron for the metallic portion; 30 but these are impractical, owing to the extra

weight and cost of metal necessary to furnish the strength in this brittle material requisite for withstanding the shocks and thrusts of service.

What I claim, and desire to secure by Letters Patent, is—

1. The improved composite tie, comprising a metallic base or retainer and elastic bearing-seats for the rails, said metallic base consisting of a rolled-metal plate having the sides bent up, and also having the retaining-flanges bent inward over and confining the bearing-seats in their position and the rails thereon, substantially as described. 40

2. The improved composite tie, comprising a metallic base or retainer and elastic bearing-seats for the rails, said metallic base consisting of a rolled-metal plate having the sides bent up, also having the retaining-flanges bent over and confining the bearing-seats in their position and the rails thereon, and also forming back supports to the rail-holding spikes, substantially as described. 50

3. The improved composite tie, comprising a metallic base or retainer and elastic bearing-seats for the rails, said metallic base consisting of a rolled-metal plate having the sides bent up and provided with reinforcing caps for retaining the bearings and the rails, said caps being placed over and spiked through the sides of the retainer to the bearing-seats, substantially as described. 60

ROBERT MORRELL.
